UNITED STATES PATENT OFFICE.

PAUL G. PATER, OF HAMILTON, OHIO, ASSIGNOR TO THE LONG & ALLSTATTER COMPANY, OF HAMILTON, OHIO.

FLOATING PUNCH.

1,298,088.

Specification of Letters Patent. Patented Mar. 25, 1919.

Application filed May 20, 1918. Serial No. 235,469.

To all whom it may concern:

Be it known that I, PAUL G. PATER, a citizen of the United States, residing at Hamilton, Butler county, Ohio, have invented certain new and useful Improvements in Floating Punches, of which the following is a specification.

This invention relates to improvements in that class of metal punches, often referred to as floating punches, designed to facilitate the accurate positioning of the plate to be punched prior to the punching stroke.

A punch, having punched a hole through a plate must, of course, in withdrawing therefrom rise a distance equal to the thickness of the plate in order to permit the shifting of the plate for a new punching. A stripping device must be present to hold the plate down while the punch is rising, and this stripper will not be nicely down upon the plate but will be some little distance above it, which distance will be called the stripper clearance. Again, as the punch withdraws from the plate, the margin of the hole may pout upwardly somewhat, the consequence being that, in order to properly clear the plate, the punch must rise at least the thickness of the plate plus the stripper clearance plus the possible pouting. Punch-construction recognizes these conditions and provides a further excess of stroke, so that the punch, in its uppermost position, very freely clears the plate and, quite likely, has such further excess of stroke as to permit of the punching of thicker plates.

In positioning the plate, prior to the punching, and assuming that the punching is not done through a templet, two plans are open to employment in the marking of the plate to indicate where the punching is to be done. One plan is to mark the outline of the intended hole by means of prick-punching or by imprinting the area of the intended hole with pigment, the other plan being to prick-punch the center of the intended hole, and provide the punch with a teat to engage this prick-punch mark. The first plan depends on eyesight, and the second plan depends on the feel of things as the teat enters the prick-punch mark during the shifting of the plate. The utilization of either plan, and particularly the second one, necessitates that, in adjusting the plate, the punch be close down to it, and this is in-

consistent with the high position of the punch following the stripping. This inconsistency has recently brought about the development of floating punches in which the punch is vertically free in the ram which operates it, the ram being connected with the punch by means of a let-go device, automatic or manual, which releases the elevated punch and permits it to descend and float upon the plate regardless of the thickness of the plate.

My present invention directs itself to a construction permitting the let-go device to be dispensed with and at the same time facilitating dealing with plates of varying thicknesses.

The invention will be readily understood from the following description taken in connection with the accompanying drawings in which:

Figure 1 is a side elevation of an ordinary punching machine fitted with my improvements:

Fig. 2 a face elevation of the movable clutch-member of the automatic clutch:

Fig. 3 a side elevation of the same:

Fig. 4 a vertical section of the same in the plane of line *d* of Fig. 2:

Fig. 5 a front view of the die:

Fig. 6 a front elevation of the ram and its punching accessories:

Fig. 7 a vertical section of the same in the plane of line *a* of Figs. 6 and 8: and

Fig. 8 a horizontal section of the ram in the plane of line *c* of Figs. 6 and 7.

A diversity of scales is employed in the drawings.

In the drawings:

1, indicates frame portions of the machine:

2, the cam shaft:

3, the ram or slide which carries the punch:

4, the die:

5, the sliding member of the automatic clutch:

6, the switch carried thereby:

7, the release-pin of the automatic clutch mechanism:

8, the plate to be punched:

9, the punch: and

10, the stripper.

All of the parts thus far referred to, with the exception of features hereinafter more

fully set forth, may be as usual in punching machines, and may be subject to any usual appropriate modification.

The usual operation of the parts thus far referred to may be briefly described as follows:—

The ram and punch are up; the cam-shaft is unclutched from the driving power and held so by the release-pin; the plate to be punched is positioned; the release-pin is lifted by momentary action on the treadle; the spring causes the clutch to engage; the ram and punch descend and make their punching stroke; they ascend and the stripping is done; the switch engages the release-pin and disengages the clutch; the punch comes to rest in upper position; the plate may be shifted for a new punching, and so on and on. The punch, being in its uppermost position, as has been assumed, would be so far above the plate as to be of little use as an aid in positioning the plate for the next punching, as has been heretofore more fully explained. The improvements will now be explained:—

Continuing with the drawings:—

11, indicates a punch-stock connecting the punch with the ram:

12, a bushing adjustably screwed into the base of the ram, the punch-stock being free to slide in the bore of this bushing; the upper end of this bushing forming an upwardly presenting abutment carried by the ram:

13, a head on the upper end of the punch-stock and adapted to engage the abutment formed by the upper end of the bushing:

14, an abutment carried by the ram above the head of the punch-stock and adapted for downward engagement with it to impart the punching force:

15, a block secured in the front of the ram at its base, the threaded bore in which the bushing is screwed being formed half in the ram and half in this block:

16, a radial set-screw through the wall of the bushing with its point loosely engaging a keyway in the punch-stock:

17, a shim under the die or die-block, this shim typifying means for vertically adjusting the top of the die:

18, a groove formed in the periphery of the movable member 5 of the automatic clutch:

19, a switch-ring surrounding and rotary upon the grooved portion of the clutch-member, this switch-ring bearing the switch 6:

20, pins screwed through the switch-ring and having their inner ends engaging the groove in the clutch-member, so as to prevent the sidewise displacement of the switch-ring without interfering with its rotation on the clutch-member: and

21, set-screws passing through the switch-ring and biting the bottom of the groove in

the clutch-member and serving to lock the switch-ring in adjusted angular position.

Looking at Figs. 2, 3 and 4, the angular shifting of the switch-ring on the movable clutch-member permits of the automatic clutch being so adjusted that the clutch will be disengaged and the cam-shaft and ram come to rest in any desired angular position of rotation of the cam-shaft. Figs. 6 and 7 assume that the cam-shaft and ram are at rest, a condition brought about by the action of the automatic clutch, and it is to be observed, from Fig. 6, that the ram is somewhat below its uppermost limit of stroke. In other words, the ram has gone up and then has made a slight descent before coming to rest, and the extent of this descent should be at least equal to the stripper clearance plus the possible pouting.

Looking at Figs. 6 and 7 the program of events of the improved device would be as follows:—

The ram is at rest somewhat below its uppermost limit of stroke; the punch is floating on the plate; the head of the punch is free from engagement by the bushing underneath it or by the abutment 14 over it; the plate may be shifted as desired until it is properly positioned for a new punching; the treadle is momentarily actuated; the clutch engages; the ram descends and its abutment engages the top of the punch-stock and forces the punch through the plate; the ram starts on its rising motion; it picks up the punch by the engagement of the bushing with the head of the punch-stock; the punch is raised sufficiently to take care of the stripper clearance and of any possible pouting; the ram having reached the top of its stroke, descends somewhat; the release-pin causes the disengagement of the clutch; the ram comes to rest; the punch has descended with the ram until it reaches the plate; the punch now floats on the plate; the conditions are as indicated in Figs. 6 and 7, with the head of the punch-stock free from engagement with the abutment or the bushing; the plate may be shifted while the floating punch is at full liberty to dance through the bushing while the new punching location is being arrived at.

The punch may descend such limited distance as is permitted by the bushing, and this distance should not be so great as to interfere with the steering of a new plate under the punch.

If the plate be withdrawn then the above mentioned program would hold good with a plate of the illustrated thickness. But if a plate of, say, half the thickness of the illustrated one were inserted, then the punch could not float down to it, being held up too high by the bushing. An adjustment must be made to take care of the new distance between the upper surface of the plate and

the ram, and this may be taken care of by raising the die, as by means of such a shim as 17, illustrated in Fig. 5, or it may be taken care of by lowering the bushing, which is to be done by loosening block 15 and unscrewing 5 the bushing downwardly the proper distance. Within certain limits it is obvious that no adjustment either of the punch or the die will be necessary, the point being that 10 the punch will be capable of floating on the plate without being sustained away therefrom by the ram. And it is also obvious that in case continuous work is being done upon plates of unvarying thickness no provision 15 whatever need be made for adjusting either the die or the punch.

Many punching machines are used also for shearing, and the loss of motion at the top of the stroke which is here employed in connection 20 with a floating punch, may be undesirable when the machine is employed for shearing. This matter is readily taken care of by simply shifting the switch-ring to such position that the ram will come to rest at its 25 topmost limit of stroke.

I claim:

1. In a floating punch, the combination, of a die, a ram reciprocable to and from the die, a stripper disposed between the die and ram, 30 a downwardly presenting abutment carried by the ram, an upwardly presenting abutment carried by the ram, a punch reciprocable in the ram, an upwardly presenting surface connected with the punch and adapted 35 for contact with the downwardly presenting abutment of the ram, a downwardly presenting surface connected with the punch and adapted for contact with the upwardly presenting abutment of the ram and located 40 at a distance from said upwardly presenting surface in excess of the distance between the two abutments of the ram whereby the punch may have a limited degree of reciprocation in the ram when the ram is at an intermediate point of its stroke, and means for arrest- 45

ing the motion of the ram when both its abutments are free of contact with the punch and said surfaces of the punch are free to reciprocate between said abutments, substantially as set forth. 50

2. A structure as specified in claim 1 in combination with means for adjusting the distance between the die and the punch when the punch is supported by the ram in stationary condition, substantially as set forth. 55

3. A structure as specified in claim 1 in combination with means for adjusting the protrusion of the punch from the ram when no plate is present for the punch to float upon, substantially as set forth. 60

4. A structure as specified in claim 1 in combination with a cam-shaft and clutch for effecting the arrest of the ram while the punch is floating on the plate, substantially as set forth. 65

5. A structure as specified in claim 4 in combination with an automatic clutch for effecting the automatic arrest of the ram while the punch is floating on the plate, substantially as set forth. 70

6. A structure as specified in claim 1 in combination with a bushing adjustably screwed into the base of the ram to form the lost motion connection between the punch and the ram, substantially as set forth. 75

7. A structure as specified in claim 6 in combination with means for locking the bushing against rotation, and a radial screw carried by the bushing and engaging a keyway in the punch, substantially as set forth. 80

8. A structure as specified in claim 6 in combination with a block clamped to the base of the ram and forming part of the threaded socket for the reception of the bushing and forming in addition a locknut 85 for the bushing, substantially as set forth.
